(No Model.)

W. H. H. CLAGUE.

FILE BOX.

No. 340,094.

Patented Apr. 20, 1886.

UNITED STATES PATENT OFFICE.

WILLIAM H. H. CLAGUE, OF ROCHESTER, NEW YORK.

FILE-BOX.

SPECIFICATION forming part of Letters Patent No 340,094, dated April 20, 1886.

Application filed August 24, 1885. Serial No. 125,138. (No model.)

To all whom it may concern:

Be it known that I, WILLIAM H. H. CLAGUE, of Rochester, in the county of Monroe, State of New York, have invented certain Improvements in File-Boxes, of which the following is a specification.

My invention has relation to that class of files, boxes, or receptacles whatever their form, which are mounted in an inclosing case or cabinet and provided with appliances by which they are automatically arrested and suspended from the cabinet when withdrawn, in order to permit convenient access to their contents.

It is the aim of the invention to improve the means employed for arresting and suspending the boxes and to permit their ready attachment when required.

Figure 1 represents in side elevation my box with its improved attachments within an inclosing case or cabinet, which latter is shown in vertical section. Fig. 2 is a top plan view of the file-box as it appears when withdrawn from and suspended in front of the cabinet, which is shown in horizontal section. Fig. 3 is a side elevation of the base portion of the file-box, showing particularly the flanged plates and studs by which it is suspended. Fig. 4 is a top plan view of one side of the base of the box, showing the parts below the dotted lines of the preceding figure. Fig. 5 is a top plan view of the sliding suspending-plate. Fig. 6 is a vertical section through the base of the forward portion of the cabinet, showing the sliding suspension in position thereon. Fig. 7 is a cross-section on the line $z-z$ of Fig. 1. Fig. 8 is a detail view showing the connection of the slide and file-box when withdrawn from the case.

A represents an inclosing case or cabinet, which may be of any suitable construction adapted to receive the file-boxes, but which is preferably constructed with vertical and horizontal partitions by which its interior is divided into pigeon-holes or compartments, each adapted to receive a single file-box.

B represents the file-box or file-holder, which may be of any approved construction, except as regards the details hereinafter described.

The box shown in the drawings is of substantially the same construction as others at present known in the art, consisting of a base-

board, *a*, a front board, *b*, secured at right angles thereto, and a follower or pressure board, *c*, united by suitable clamping or fastening devices with guide-arms *d*, so that it may be moved to and from the base-board *a*, for the purpose of confining the paper or other articles between them. In this form of box the base-board *a* and follower *c* and the papers between them stand in a horizontal position when the box is within the case or cabinet, so that when the box is withdrawn it must be tipped or turned to present the paper in an upright position, that they may be inspected or removed.

In applying my improvement I provide the horizontal back board or base, *a*, of the box, along each edge, with a metallic plate, *C*, extending from the front of the box rearward half its length or thereabout. This plate, which is secured firmly to the box by screws or other fastening, is provided along its rear edge with an outwardly-extending flange, *e*, which terminates near the front, for a purpose which will presently appear. Near its inner or rear end I provide the plate with an outwardly-extending stud or other rigid stop, *f*, and at its forward end I provide it with one or more studs or other rigid stops, *g*.

Within the case or cabinet, near the front, I mount a transverse sliding plate, *F*, of the form plainly represented in Figs. 5, 6, and 8. This consists of a cross-bar seated in a recess in the bottom of the case, and provided at its extremities with two horizontal sliding arms 85 seated on pins *h* at the sides of the box, as shown particularly in Figs. 5, 6, and 7, this arrangement permitting the plate to slide forward and backward to a limited extent in a horizontal position. The arms of the plate *F* are provided at their forward ends with inwardly-projecting pins or studs *i*, which engage over the flanges *e* of the plate *C*, for the purpose of guiding and holding the file-box and connecting the same with the cabinet, as will 95 hereinafter appear. When the box is turned upward and pushed into the case, as represented in Fig. 1, the plate *F* is moved inward and assumes the position shown in Fig. 1. As the box is drawn outward, however, its flanges 100 *e* slide beneath the studs of the plate *F* until the box projects half its length or thereabout

beyond the cabinet, whereupon the studs *f* of the box engage the studs *i* of the plate *F*, and slide the latter forward until its arms project beyond the front of the cabinet, when the box 5 will tip downward and outward upon the studs *i* as pivots, until it assumes the position represented in full lines in Figs. 2 and 8, and dotted lines in Fig. 1. When thus suspended, the papers are presented in an upright position, 10 and the box is firmly sustained in front of the cabinet by the flanges *e* and studs *f* engaging studs *i* of the plate *F*, as plainly represented by the dotted lines.

It is to be noted that the action of the parts 15 is entirely automatic, and that in order to effect the suspension of the box the operator has only to draw the same forward and release it. If it be desired to disconnect the box from the cabinet, it is only necessary to draw it forward 20 sufficiently for its front board, *b*, to clear the front of the cabinet, whereupon it may be lifted until the forward ends of the flanges *e* pass above the studs *i*, which release the box, so that it may be removed. The form of the 25 stops *f* and *g* at the two ends of the plate *C* is not material. Studs, flanges, or other projections of any suitable form which will engage the studs *i* of the sliding plate, may be employed. The plate *F* is inserted by springing 30 its arms inward, as indicated by dotted lines in Fig. 5, then placing it in position and permitting the arms to spring outward, so as to receive the pins within their slots.

I claim—

35 1. In combination with the inclosing case or cabinet, a file-box having flanged plates *c*, attached to its opposite edges, and two side bars or arms provided with studs to engage the flanged plate and attached to slide horizontally in the cabinet at opposite sides of the file-box, whereby the box is sustained at both sides and permitted to tip downward when withdrawn from the case.

2. The supporting case or cabinet and a file-box provided with the horizontally-flanged 45 plates *C*, in combination with the sliding file-box support *F*, having its arms united by sliding connections with the case and its extremities provided with studs to engage the flanged plates of the file-box and suspend the same 50 when withdrawn.

3. In combination with the cabinet or receptacle, the file-box *B*, substantially as described, the plates *C*, secured to the edges of the file-box and each provided with flanges *e* and stops *f*, and the plate *F*, attached by a sliding connection to the case and provided at its forward end with studs *i*. 55

4. In combination with an inclosing case or cabinet and the sliding bar having inwardly-projecting studs *i*, the plate *C*, provided with stops *f* and flanges *e*, the latter terminating at a distance from the trunk of the file-box, whereby by the boxes may be detached and removed, as desired. 60

5. The combination, with the case or cabinet, of the cross-bar *F*, having the horizontal slotted arms and inwardly-projecting studs *i*, pins attached to the case and entering said slots, the file-boxes, and the plates *C*, secured 70 to the file-box and provided with a flange, *e*, and stops *f* and *g*. 65

6. In combination with a file-box, an inclosing case or cabinet with guide-pins *h* at its sides and the sliding plate *F*, provided with 75 elastic slotted arms adapted to spring outward into engagement with the guide-pins, as described, whereby the disconnection of the slide is permitted at will.

In testimony whereof I hereunto set my hand, 80 this 29th day of July, 1885, in the presence of two attesting witnesses.

WILLIAM H. H. CLAGUE.
